UNITED STATES PATENT OFFICE.

JAS. M. THOMPSON, OF HOLYOKE, MASSACHUSETTS.

IMPROVEMENT IN OIL-DRIPPERS.

Specification forming part of Letters Patent No. **13,406**, dated August 7, 1855.

To all whom it may concern:

Be it known that I, JAMES M. THOMPSON, of Holyoke, in the county of Hampden and State of Massachusetts, have invented a new and Improved Oil-Dripper; and I do hereby declare that the following is a full and exact description thereof, reference being had to the accompanying drawings, making a part of this specification, in which—

Figure 1 is an isometrical view, and Fig. 2 is a vertical section, (part of the outside being removed in Fig. 1 to show the internal arrangement.)

The same letters indicate like parts in each figure.

E, Fig. 2, is a chamber formed within the dripper by the partitions *a* and *b*.

C is a tube leading through the top *A* of the dripper into the chamber E, diverging from the center of the dripper, and nearly parallel to the conical top, and terminating at sufficient distance from the horizontal partition *a* to admit air freely to the chamber E.

F is another tube leading from the chamber at the opposite side from the termination of tube C, through the partition *a*, down into the body of the dripper in a line parallel to tube C, and terminating near the bottom and side of the dripper. The dripper should not be

filled quite up to the partition *a*, as there should be no oil in the chamber at any time except what runs from the tube F when the dripper is inverted to allow the oil to escape through the stem B, and, as the capacity of the chamber is much larger than the capacity of the tube C, the oil passing from the tube F into the chamber will leave the tubes C and F free to admit air to the bottom of the dripper, thus securing a free drop or stream from the stem, (as determined by the size of the hole,) and preventing the escape of any oil except through the stem. The top *A* of the dripper is placed a little below the top of the conical sides, forming a recess to catch the oil that runs down on the outside of the stem, and return it to the dripper through the vent, keeping the outside of the dripper always clean.

What I claim as my invention, and desire to secure by Letters Patent, is—

The arrangement of the chamber E, in combination with the tubes C and F, as constructed, for the purpose specified.

JAMES M. THOMPSON.
